UNITED STATES PATENT OFFICE.

AMBROSE N. DIEHL, OF DUQUESNE, PENNSYLVANIA.

HOT-BLAST STOVE.

Application filed August 8, 1921. Serial No. 490,527.

To all whom it may concern:

Be it known that I, AMBROSE N. DIEHL, a citizen of the United States, and resident of Duquesne, in the county of Allegheny and 5 State of Pennsylvania, have invented certain new and useful Improvements in Hot-Blast Stoves, of which the following is a specification.

My invention relates to the construction 10 of hot blast stoves employed in heating the air used in blast furnaces, and while not limited thereto, the invention relates more particularly to the construction of the top of a two-pass stove of the central combustion 15 chamber type.

In such stoves the cylindrical plate metal shell is lined with refractory material and is provided with checker-work formed of fire brick or similar refractory material. In 20 using the stoves the refractory walls forming the channels or passages in the checker-work are heated to a high temperature by burning gases in the central combustion chamber and causing the burned gases or 25 products of combustion to pass through the passages in the checker-work in the travel thereof to the stack through which the products of combustion are led from the stoves. After each heating operation the cold blast, 30 or air under considerable pressure, is passed into and through the stove and is heated by contact of the air with the surfaces of the highly heated checker-work.

In stoves of this type as constructed heretofore, the products of combustion, in the passage thereof through the stove, form an annular dead space or pocket of still gases immediately above the upper end of the checker-work, and the presence of this pocket 40 of still gases causes an uneven distribution of the products of combustion within the distributing chamber above the upper end of the checker-work. The result has been that the vertical passages in the checker-work adjacent to the outer wall or lining of the 45 stoves and the annular row of passages in the checker-work adjacent to the walls forming the central combustion chamber, receive the major portion of the products of combustion, while the intermediate annular rows 50 of passages in the checker-work, or those immediately beneath the pocket, receive little or none of them.

One object of my invention is the provision in a hot blast stove of novel means

whereby the formation of such pockets of still gases within the distribution chamber is avoided and overcome, the burned gases or products of combustion are uniformly distributed over the top of the checker-work 60 and are caused to flow through all of the passages in the series of rows of vertical passages within the checker-work and the thermal efficiency of the stove is materially increased.

Another object of the invention is the provision in a hot blast stove of novel means for distributing and directing the flow of the burned gases into the series of rows of vertical passages in the checker-work of the stove 70 that may readily be applied to existing stove structures without material changes in the stove structure.

Referring now to the drawings forming part of this specification, Figure 1 is a vertical sectional elevation, partly broken away, showing a hot blast stove having my invention applied thereto.

Figure 2 is a sectional plan of the apparatus of Figure 1, the section being taken on 80 the line II—II of Figure 1.

Figure 3 is a similar sectional plan taken on the line III—III of Figure 1.

Figures 4 and 5 are anemometer charts showing the results obtained before and after 85 the application of my invention to a hot blast stove, in a series of tests made for that purpose.

Figure 6 is a vertical section of the upper end of a hot blast stove of the usual construction illustrating the way in which the dead spaces or pockets form above the upper end of the checker-work and the resulting unequal distribution of the products of combustion within the distribution chamber and 95 into the vertical passages formed by the checker-work.

Figure 7 is a similar vertical section illustrating the way the annular dead spaces or pockets are eliminated and the flow of the 100 products of combustion is directed within the distribution chamber so as to supply the products of combustion to all of the vertical passages formed by the checker-work within the stoves embodying my invention.

In the accompanying drawings, the numeral 2 designates the metal shell of a hot blast stove having a central combustion chamber 3, and being provided with the usual cold blast inlet 4, stack 5, and stack valve 6. The 110

2

stack 5 and cold blast inlet 4 open into the passage 7, which in turn opens into the outer end of the horizontal flue 8. The flue 8, which is located below the bottom of the 5 stove, has its inner end connected with the vertical flue 10, which extends upwardly into the chamber 11 in the bottom of the stove, this chamber being on the axial center of the stove.

10 An annular wall 12 forms the combustion chamber 3, and a second annular wall 13 forms the outer wall or lining of the stove. The space between the wall 12 and wall or lining 13 forms an annular lengthwise vertical chamber which contains the stove 15 checker-work. This checker-work as shown comprises a series of radial walls 14 and intersecting series of annular walls 15, forming a multiplicity of lengthwise vertical passages 16, through which the products 20 of combustion pass downwardly in heating the stove checker-work.

The vertical passages 16 open into the distributing chamber 17 which is located at 25 the top of the stove above the upper end of the checker-work, this chamber 17 having a dome-shaped refractory lining 18 which is supported on and built integral with the refractory lining or side wall 13. 30 The passages 16 are in open communication with the upper end of the combustion chamber 3, through the medium of the distributing chamber 17 so that the products of combustion pass from the combustion chamber, through the distributing chamber 17, into the vertical passages 16 and, after 35 traversing the vertical passages 16, emerge into the chambers 22, and pass through the radial passages 21 into the chamber 11, and 40 thence out of the stove by way of passages 10 and 8 into the stack 5, the stack valve 6 being open at such time.

The combustion chamber 3 is provided with a refractory bottom 19 which is spaced 45 some distance above the bottom 20 of the stove and forms a top or roof for the chamber 11. The stove is provided with the usual complement of gas and air inlets, relief valves and other necessary appliances. 50 These not forming part of this invention are not shown and will not be further described.

In stoves of this type as constructed heretofore, the products of combustion flowing 55 out of the combustion chamber 3 into the distributing chamber 17 impinge against the top or roof 18 of the stove and, due to centrifugal force and other natural and artificial forces, are held close to the roof 60 18 and directed toward the outer wall or side of the stove. This results in the major portion of the products of combustion entering the passages 16 nearest to the side 13 of the stove and some of the products 65 of combustion enter the passages 16 nearest

the wall forming the central combustion chamber. A considerable portion of the passages, (those located midway between the wall 12 and wall 13) receive little or none of the gases. Stated another way, 70 an annular pocket or dead space filled with still or inert gases forms immediately above the upper end of the checker-work, with the result that the entering products of combustion form currents and flow into the 75 annular rows of passages in the checker-work closest to the stove side wall 13 and to the annular wall 12, and do not to any extent flow into the intermediate rows of 80 passages. (See Figure 6).

In order to avoid and prevent the formation of the annular dead space or pocket in the distribution chamber 17, and in order to cause the products of combustion to be uniformly distributed over the entire area 85 above the checker-work, an annular deflecting ring or baffle 23, having converging upper and lower faces 24 and 25 respectively, is provided within the distribution chamber 17 on the wall 13 of the stove at 90 a point immediately above the upper end of the checker-work.

In the operation of stoves equipped with my invention, the products of combustion emerge from the combustion chamber 3 into the distributing chamber 17, impinging upon the roof 18 of the distribution chamber 17 and flowing outward toward the outer wall 13 of the stove. The flowing products of combustion, upon striking the inclined surface 24 of the deflecting ring or baffle 23, are retarded and deflected inwardly toward the vertical center of the stove. In this way the dead space usually occupied by the still gases or products of 105 combustion is eliminated and the flowing gases are directed into the upper ends of the intermediate rows of passages in the checker-work, as well as into those adjacent to the periphery of the stove and to the 110 inner series of passages next to the wall 12 forming the central combustion chamber. The uniform distribution resulting from the use of the deflector ring or baffle 23 will be readily seen by comparing Figures 4 and 5 and by reference to Figures 115 6 and 7.

In Figures 4 and 5, in which the lines 26 and 27 designate the walls defining the transverse dimensions of the passages 16 of 120 the checker-work, the numerals within each space represent the relative velocities in feet per minute at which the products of combustion flow through the multiplicity of passages 16. In Figure 4 it is shown that 125 without the use of the deflector ring or baffle 23, the outer three annular rows of passages 16 receive most of the products of combustion, while the amount of products of combustion entering the next three annu- 130

lar rows is practically zero, and that the innermost annular row of passages received less than either of the outer three rows. The cause of this effect is illustrated in Figure 6.

By reference to Figures 5 and 7, it will be seen that in stoves equipped with my invention, the products of combustion are uniformly distributed over the area immediately above the checker-work within the distribution chamber 17, and that each of the annular rows of vertical passages 16 of the checker-work receives practically the same volume of the highly heated gases, with the result that all of the passages are uniformly heated and each of the passages is heated so as to perform its part of the work in heating the cold air afterward passed therethrough to form the hot blast for the blast furnace.

While a preferred embodiment of my invention is shown herein, the invention is not to be limited thereto, since various modifications thereof may be made without departing from my invention as defined in the appended claims.

I claim:-

1. The combination with a hot blast stove having the usual outer wall, central combustion chamber and intermediate checker-work, of means spaced above and independent of said checker-work for directing the flow of products of combustion from said combustion chamber, said means being adapted to effect a substantially even distribution of the products of combustion within the passages of said checker-work.

2. The combination with a hot blast stove having the usual outer wall, central combustion chamber and intermediate checker-work, of a baffle ring above said checker-work for directing the flow of products of combustion from said combustion chamber, said baffle ring being constructed and arranged to effect a substantially uniform distribution of the products of combustion within the passages of said checker-work.

3. In a hot blast stove having the usual outer wall and dome-shaped top, the combination of a central combustion chamber, checker-work surrounding said combustion chamber, said checker-work forming a multiplicity of lengthwise vertical passages connected with the combustion chamber at the upper end of the stove, and an annular deflector on the inner face of said outer wall

above the upper end of said checker-work, said deflector being adapted to direct the flow of products of combustion above the upper end of said checker-work, and thereby cause a substantially uniform distribution of the products of combustion within the passages of said checker-work.

4. In a hot blast stove having the usual outer wall and dome-shaped top, the combination of a central combustion chamber, checker-work surrounding said combustion chamber, said checker-work forming a multiplicity of lengthwise vertical passages connected with the combustion chamber at the upper end of the stove, and an annular deflector ring on the inner face of said outer wall, said deflector ring being positioned adjacent to the juncture of said dome-shaped top with said outer wall and extending into the flow path of the products of combustion, to thereby interrupt and deflect the flow of said products of combustion and cause a uniform distribution thereof within the passages of said checker-work.

5. The combination with a hot blast stove having the usual outer wall, central combustion chamber, and intermediate checker-work, of a baffle ring on the inner surface of said outer wall above the upper end of said checker-work, said baffle ring having inclined sides adapted to distribute the products of combustion above the upper end of said checker-work and thereby cause a substantially uniform distribution of said products of combustion into the passages in said checker-work.

6. The combination with a hot blast stove having the usual outer wall, central combustion chamber, and annular set of vertical flues, of means for retarding the flow of products of combustion along said outer wall.

7. The combination with a hot blast stove having the usual outer wall, central combustion chamber, intermediate checker-work and distribution chamber above said checker-work, of means within said distributing chamber for directing the flow of products of combustion into the passages of said checker-work to thereby uniformly distribute said products of combustion within the plurality of rows of passages in the checker-work.

In testimony whereof, I have hereunto set my hand.

AMBROSE N. DIEHL.
